UNITED STATES PATENT OFFICE.

BERNARD L. POLOSKIE, OF LANCASTER, PENNSYLVANIA.

AUTOMOBILE CURTAIN.

Application filed September 14, 1925. Serial No. 56,264.

This invention relates to improvements in automobile curtains by which the same may readily be raised or lowered or rolled up.

5 The object of this invention is to provide a simple, durable and reliable construction for the various elements, and to provide an arrangement which will readily permit temporary raising and lowering of the curtain 10 at will, and which is adapted for rolling up into small compass when its use is not desired.

Other objects will be apparent and this invention will be more fully understood 15 from the following description, taken in connection with the accompanying drawing, forming a part hereof, and in which similar numerals refer to similar parts throughout the several views.

20 Fig. 1 is an elevation of the inner side of my curtain.

Fig. 2 is an end view of Fig. 1.

Fig. 3 shows the curtain in the rolled up condition.

25 Fig. 4 is a detail drawing of the upper connection for the vertical member 9 as shown in Fig. 1.

Fig. 5 is a plan view of Fig. 4.

Fig. 6 is a side elevation of Fig. 4.

30 Fig. 7 is a detail drawing of the lower connection for the vertical member 9 as shown in Fig. 1.

Fig. 8 is a side elevation of Fig. 7.

With reference to the drawing, 10 represents a portion of the frame structure of an ordinary automobile top. 11 is an anchor block which forms a continuation of the vertical member 9 and is anchored to the structure 10 through the device represented 40 in Figs. 4, 5 and 6. The vertical member 9 is connected to the anchor block 11 through the hinge 12; this hinge is shown in detail in Figs. 4 and 6, and is fully described and forms the subject matter of my application 45 for patent filed April 28, 1924, and bearing Serial No. 709,499. The operation of this hinge is here briefly described as follows:— Two contractile springs 14 have their ends connected to the pins 15 and 16, and arranged to draw around the roller 17 and pull the vertical member 9 in the direction indicated by arrow 18 when the same is turned down as shown in Fig. 2, and thereby hold the curtain snuggly against the side 50 of the automobile body 59; but when the

vertical member 9 is turned up to the position shown in light broken lines in Fig. 2, the springs 15 then draw to hold the curtain up, pulling it in the direction indicated by arrow 19.

60 The curtain 20 is attached in any usual manner to the frame structure 10, and has attached to its lower end a cross member 21. The cross member 21 is connected to the vertical member 9 through the device shown in 65 detail in Figs. 7 and 8.

The object of my construction as shown 70 is to provide means whereby the anchor block 11, or in other words, the upper end of vertical member 9 may be disconnected from the frame structure 10 and turned in the direction indicated by arrow 22 to a position parallel with the cross member 21 as shown in light broken lines in Fig. 1, after which the curtain 20 may be rolled 75 up upon the members 9 and 21 as shown in Fig. 3. After the curtain is rolled in this manner the same may be hooked up to the frame structure 10 by straps 23, or in some similar fashion.

80 When the upper end of the vertical member 9 is disconnected from the frame structure 10, the normal action of the spring 14 will tend to bend the hinge 24 as indicated by arrows 25, and the anchor block 11 will 85 then stand at an angle with the vertical member 9, and on account of this it will be inconvenient to roll up the curtain; therefore, I provide a latch 26 which is pivoted to the member 9 through the screw 27, and 90 arranged so that it may be turned to a position as shown at 28, or 29, when it is not needed and where it will not interfere with the normal action of the springs 14 in holding the lower end 30 of the curtain against 95 the side of the automobile body 59. When it is desired to roll up the curtain the latch 26 should be turned to the position shown in full lines in Fig. 4, and when in this position it will bear against the anchor block as 100 shown at 31 and hold the same in straight alignment with the vertical member 9. The curtain may then be conveniently rolled up.

105 For disconnecting the upper end of the vertical member from the frame structure 10, the procedure is to turn the latches 34 in the directions indicated by arrows 35 to the positions shown in light broken lines. The upper end of the vertical member 9 is then moved in the direction indicated by 110

arrow 36 until the stud 37 clears the edge 38 of the latch bracket 39, then it is moved in the direction indicated by arrow 40. The upper end of the vertical member 9 is now 5 released and it may now be turned in the direction indicated by arrow 22 to the position shown in light broken lines in Fig. 1. For reconnecting the upper end of the vertical member 9 to the frame structure 10, the 10 opposite procedure of course must be carried out. A nut 41 is arranged to screw on the stud 37 and may be used to tighten the anchor block 11 firmly to the latch bracket 39; however I prefer that the stud 37 be 15 free enough to turn on its vertical axis in the latch bracket 39 so that the lower end 30 of the curtain can adapt itself to the line of the automobile body 59, regardless of what angle the cross member 21 may 20 take relative to the frame structure portion 10. However in any event the nut 41 serves to hold the vertical member against slipping down in the direction indicated by arrow 42, and thereby putting undue strain 25 upon the curtain 20.

The latches 34 are carried by the screws 43 and arranged to turn thereon. The screws 43 of course are fixed to the latch bracket 39. The latch bracket 39 is fixed to 30 the frame structure 10 through the screws 44.

The lower connection of the vertical member 9 to the cross member 21, consists of a hinge formed by the two plates 45 and 46, these plates being fixed to the cross member 35 21 through the screws 64; and a pivot pin 47 which passes through the two plates and member 9, and thereby forming a hinge, it being apparent that the vertical member 9 may readily be turned in the pivot pin 47.

40 As a latching device to prevent turning of the cross member 21 relative to the vertical member 9, I provide two screw eyes 48 and 49 which are screwed into the member 9, and a slidable pin 50 arranged to slide 45 through the screw eyes and engage with a hole 51 in the cross member 21. It is apparent that when the slidable pin 50 is in engagement with the hole 51, the cross member 21 cannot turn to any harmful extent, 50 particularly in the direction indicated by arrow 52; this is indicated by a line in the form of an arc 53 which is drawn with its center on the center of the pivot pin 47, and shows that sufficient stock is present 55 between the line 53 and the hole 51 to prevent such turning action. The cross member 21 cannot turn in the direction indicated

by arrow 54 for the reason that the heel 55 of the member 9 will prevent such movement.

The spring 56 is provided to normally 60 hold the slidable pin 50 into engagement with the hole 51; the upper end 57 being attached to the pin 50 by passing through a hole therein, and the lower end 58 is hooked around the screw eye 49 as shown. The 65 spring 56 is normally under tension and draws the slidable pin 50 in the direction indicated by arrow 58. After the vertical member 9 is disconnected at its upper end from the frame structure 10, it is necessary 70 to release the slidable pin 50 from the hole 51, by pulling on the head 63 against the action of the spring 56, before turning the vertical member in the direction indicated by arrow 22. 75

To insure that the vertical member 9 will stay in its parallel position relative to the cross member 21 during the manipulation of the curtain, I provide a spring latch 59 which is fixed to the cross member 21 and 80 arranged to grip the vertical member 9 by reason of its hooked end 60. To release the vertical member 9 it is only necessary to push on the end 60 as indicated by arrow 61. The spring latch 59 again assumes its original 85 position as shown through the resiliency of the body portion 62.

Having thus described my invention, what I claim and desire to secure by Letters Patent is as follows:— 90

1. The combination with a curtain, of a cross member attached to the lower end of said curtain, a vertical member the lower end thereof being hinged to said cross member, a stud in the upper end of said vertical member, a latch bracket having a groove arranged to receive said stud, and latches pivotally connected to said latch bracket and arranged to hold said stud in said groove. 95

2. The combination with a curtain, of a cross member attached to the lower edge of said curtain, a vertical member the lower end thereof being hinged to said cross member, an anchor block hinged to the upper end of said vertical member, springs 105 arranged to normally turn said anchor block relative to said vertical member, and a latch pivotally connected to said vertical member and arranged to hold said anchor block in true alignment with said vertical member 110 against the action of said springs.

In testimony whereof, I affix my signature.

BERNARD L. POLOSKIE.
